GIRDLE AND STIFFENING UNIT

Henry M. Herbener, Thomasville, Ga.

Application November 21, 1946, Serial No. 711,255

13 Claims. (Cl. 2—36)

1

My invention relates to girdles and to a stiffening unit to be applied thereto or to other garments.

An important object of the invention is to provide a stiffening device to be attached to the girdle or the like and having short ribs carried by the end or ends of the long rib, to prevent the jabbing action of the long rib.

A further object of the invention is to provide a stiffening device which may be produced as a completed unit, to be sold as such, and subsequently attached to the garment.

A further object of the invention is to provide a device of the above mentioned character, including a body portion having the maximum strength adjacent to the end or ends of the short rib or ribs.

A further object of the invention is to provide a device of the above mentioned character which is free from unfolded cut edges.

A further object of the invention is to provide a device of the above mentioned character, the elements of which will remain properly assembled prior to the device being secured to the garment.

A further object of the invention is to provide a device of the above mentioned character which will remain substantially flat in the proper position when secured to the garment and is sufficiently resilient to permit of the proper turning action of the short rib or ribs.

A further object of the invention is to provide a stiffening unit of the above mentioned character, which is neat in appearance, strong, durable, thin and easy to apply to the garment.

A further object of the invention is to provide means for preventing the vertically elastic back portion of a girdle from wrinkling or folding in use, without impairing its elasticity.

A further object of the invention is to provide means for fixedly attaching a stiffening rib near one end in an elastic elongated pocket, so that the pocket can slide upon the rib throughout the major portion of the length of the rib.

Other objects and advantages of the invention will be apparent during the course of the following description.

In the accompanying drawings forming a part of this application and in which like numerals are employed to designate like parts throughout the same,

Figure 1 is a perspective view of a girdle embodying my invention.

Figure 2 is a plan view of the blank from which the body portion of the stiffening unit is formed,

2

Figure 3 is a plan view of a blank for forming the resilient side of the unit.

Figure 4 is an exploded perspective view of the body portion and resilient side, prior to assembling,

Figure 5 is a perspective view of the body portion and resilient side, assembled, for forming the stiffening rib holding casing.

Figure 6 is a central longitudinal section through the casing, with the transverse tape attached at one end to the casing, taken on line 6—6 of Figure 5.

Figure 7 is a perspective view of the casing, with the tape extending across the resilient side, with one end unattached.

Figure 8 is a perspective view of the stiffening element.

Figure 9 is a perspective view of the completed casing having the stiffening element therein,

Figure 10 is a central longitudinal section taken on line 10—10 of Figure 9.

Figure 11 is a perspective view of the completed stiffening unit applied to the inner face of the front panel of the girdle.

Figure 12 is a horizontal section taken on line 12—12 of Figure 11.

Figure 13 is a similar view taken on line 13—13 of Figure 11.

Figure 14 is a similar view taken on line 14—14 of Figure 11.

Figure 15 is an exploded perspective view of the elements forming a modified form of resilient side for the rib holding casing.

Figure 16 is a perspective view of the assembled elements forming the modified resilient side.

Figure 17 is a central longitudinal section through a rib holding casing embodying the modified resilient side.

Figure 18 is a perspective view of a modified form of girdle having the stiffening units applied to its outer face.

Figure 19 is an inner side elevation of the rear panel of a girdle, having my stiffening units applied thereto.

Figure 20 is an enlarged perspective view of the rear panel and associated elements, parts broken away.

Figure 21 is a longitudinal section taken on line 21—21 of Figure 20.

Figure 22 is a side elevation of the stiffening rib shown in Figures 19 to 21.

Figure 23 is a side elevation of the inner face of a back panel of a girdle and associated elements, parts broken away.

Figure 24 is a fabric blank for forming means to secure the rib to the elastic portion of a garment.

Figure 25 is a perspective view showing the blank partly folded.

Figure 26 is an edge elevation of the same.

Figure 27 is a perspective view of the completely folded and assembled blank and stiffening rib, showing the same applied to the elastic portion of a garment.

Figure 28 is a longitudinal section taken on line 28—28 of Figure 27.

Figure 29 is a side elevation of a flexible strip, having one end secured to the elastic portion of the garment, before folding the strip to the closed position.

Figure 30 is a side elevation of the strip and elastic portion, showing the strip in the closed position and stitched to the elastic portion.

Figure 31 is a longitudinal section taken on line 31—31 of Figure 30.

Figure 32 is a longitudinal section taken on line 32—32 of Figure 30.

In the drawings, where for the purpose of illustration are shown preferred embodiments of my invention, attention being called first to Figures 1 to 14 inclusive, the numeral 10 designates an elastic girdle comprising sides 11 which are preferably two way stretch, a front panel 12 which is preferably non-elastic and a back panel 13 which is one way vertically elastic. This girdle is of the general construction shown in my Patent 2,136,742.

The numeral 14 designates stiffening units, secured to the front panel 12, substantially vertically arranged, and extending from the top of the front panel downwardly for about one third of the length of the front panel, although this may be varied. Since the front panel 12 is non-elastic, the stiffening units 14 are positioned upon the inner face of this panel.

Each stiffening unit includes a body portion 14' formed from an elongated rectangular fabric blank 15, which is preferably non-extensible. This blank is preferably formed of a light flexible strong fabric, such as "nylon." The blank 15 is folded upon longitudinal lines 16, to provide a side 17 and side sections 18 and folded edges 19. The inner edges of the side sections 18 abut but do not overlap. The longitudinally folded blank is then folded upon transverse lines 20 to provide pocket walls 21.

The numeral 21' designates a longitudinally elastic strip or side, foldable upon transverse lines 22, affording reinforcing inturned flaps 23.

The folded ends of the elastic side 21' are now inserted into the pocket walls 21, between the sides 17 and side sections 18 thereof, and are secured to these pocket walls 21 by transverse lines of stitching 24, which pass through these assembled parts only. The assembled body portion 14' and elastic side 21' now lie substantially flat, in superposed relation and constitute a stiffening element or rib receiving casing. The side 21' is narrower than the body portion 14' and the body portion has its longitudinal edges extending laterally beyond the elastic side 21'.

The numeral 25 designates a horizontal transverse retaining tape or band, which is applied to the outer face of the elastic side 21', but is not stitched or otherwise secured thereto so that the elastic side may move with relation thereto. One folded end of this tape is sewed or tacked to the body portion 14' by a line of stitching 26.

The stiffening element is preferably of the form

shown in my co-pending application for Girdle or the like, filed November 10, 1945, Serial No. 627,857. This stiffening element includes a long resilient rib 27, and short stiff ribs 28, hinged to the opposite ends of the long rib to provide knee joints, as shown. The stiffening element is now passed between the assembled body portion 14' and the elastic side 21', and is enclosed within the casing. The opposite end of the tape 25 is folded inwardly and sewed or stitched to the body portion 14' by a line of stitching 30. This tape retains the stiffening element within the casing.

I contemplate forming the inner side of the casing of a short section of longitudinally elastic fabric 32, Figures 15, 16, and 17. I provide flexible attaching elements 33 for the elastic section 32. Each attaching element is formed of a section of non-elastic fabric, such as "nylon," folded upon itself upon longitudinal lines to provide a side 34 and side sections 35. The elastic section 32 is slightly narrower than the attaching element 33 and its end is inserted into the end of the same and secured thereto by a transverse line of stitching 36. The outer ends of the attaching elements 33 are inserted between the layers of the pocket side 21 and are secured thereto by lines of stitching 37.

The assembled elements thus described constitute a completed stiffening unit, which may be made and sold as such, and may be applied to any garment, when desired. I contemplate omitting the intermediate portion of the body portion 14', between the lines "a," Figure 4, and I would then omit the tape 25.

As shown in Figure 1, two of these stiffening units 14 are arranged upon the inner face of the front panel 12, as stated, since the front panel is non-elastic. The body portion 14' is next to the panel. The stiffening units are secured to the front panel 12 by longitudinal lines of stitching 38 passing through the body portion 14' pocket sides 21 and the front panel 12, Figure 11, but not through the elastic side of the casing, nor through the attaching elements 33 or the elastic section 32, Figures 15, 16, and 17. The pocket walls or sides 21 form with the body portion 14', pockets 32', receiving the outer ends of the short ribs 28, the hinge joints occurring near the lines of stitching 24. The flaps 23 extend longitudinally inwardly beyond these lines of stitching and provide a reinforced two layer formation for engagement with the inner ends of the short ribs. The pockets 32' which receive the outer ends of the short ribs have opposite sides which are of two layer formation. The stiffening units 14 may also be secured to the inner face of a non-elastic lining, arranged upon the inner face of the panel 12, and this lining would thus serve to attach the units 14 to the panel 12 or garment.

When applied to the front panel, as shown in Figures 1 and 11, the upper short ribs turn upon their hinges to follow the curvature of the body, as the wearer stoops forwardly, thus preventing the jabbing action by the upper ends of the long ribs. The lower short ribs follow the curvature of the body and prevent the lower ends of the long rib jabbing the wearer.

As shown in Figure 18, a longitudinally elastic front panel 12' is substituted for the front panel 12, other parts of the girdle remaining the same as described in connection with Figure 1. Since the front panel 12' is longitudinally elastic, the stiffening units 14 may be applied to the outer face of the front panel 12', with the elastic side

21' next to the panel 12'. The body portion 14' of the unit 14 is stitched to the front panel 12' by lines of stitching 39, terminating at the hinges of the short ribs, and intermediate lines of stitching 40. The elastic side 21' may be omitted, if desired.

In Figure 1, I have shown stiffening units 14^a, corresponding to the units 14, arranged upon the inner face of the sides 11, and stitched thereto as indicated in connection with the stiffening units 14. Since the sides 11 are elastic, the stiffening units 14^a may be arranged upon the outer face of the sides 11, Figure 18, with the modification of the stitching, as described in connection with Figure 18. The stiffening units 14^a are shorter than the stiffening units 14, but are otherwise identical with the same. The stiffening units 14^a extend vertically from the top of the girdle, and are spaced, and any suitable number of them may be used.

In Figures 19 to 21, I have shown the rear panel or portion 41 of a girdle, which panel is vertically elastic. The panel or portion extends to the top of the girdle. Preferably arranged upon the inner face of the panel or portion 41 are vertically elastic strips or tapes 42. The upper end of each tape is folded downwardly upon itself forming a flap 43. The numeral 44 designates a stiffening rib, Figure 22, arranged between the strip or tape 42 and the panel or portion 41. This rib is provided adjacent to its upper end with an elongated horizontal slot 45. The strip or tape is attached to the panel or portion 41 by longitudinal lines of zig-zag stitching 46, and is further attached to the panel or portion 41 adjacent to the top of the garment, by a horizontal line of stitching 47, passing through the slot 45, and connecting the strip 42, flap 43 and panel 41.

It is thus seen that the top end of the rib 44 is fixedly secured to the garment panel or portion 41, at the top end of the rib and garment, while the casing or pocket formed by the strip or tape 42 and panel 41 is freely longitudinally slidable upon the rib 44, throughout substantially the entire length of the rib. By providing this construction at the back of the garment, when the user stoops forwardly or sits down, the panel or portion 41 is free to stretch longitudinally with relation to the rib 44. When the tension is relieved, the panel or portion 41 returns to the normal condition, but there is no tendency for the panel or portion 41 to fold or wrinkle, as it is held substantially flat by the ribs 44. While I have shown these ribs and associated elements applied to the back portion of the garment, they may be applied to any other portion of the garment, as found desirable.

In Figure 23, the ribs 44 may be applied to the back portion or panel 41' of a girdle having a band 48 at its top, provided with transverse stiffening ribs 49, as shown in my Patent 2,136,742. When this is done, the elastic strips or tapes 42 extend over the edge of the band 48, between the ribs 49, and terminate near the transverse center of the band 48, between the ribs. The strips 42 are held in place by the lines of stitching 46 and the same transverse line of stitching 47 is employed, to fixedly attach the top end of the rib 44 to the band 48. The ribs 44 extend to and beyond the top of the panel or portion 41', and retain the top portion of the panel flat, but permit of the longitudinal stretching of the portion 1' with relation to the ribs 44, for the reasons stated in connection with Figure 19.

In Figures 24 to 28 inclusive, I have shown a further construction for fixedly securing one end, such as the upper end, of the rib to an elastic portion of the garment. In connection with this form of invention, the numeral 49 designates a fabric blank which is longitudinally elastic. This blank is foldable upon longitudinal lines 50 to form a side 51 and side portions 52. One end of the folded blank is then folded transversely upon a line 53, Figure 25, forming an inner flap 54, stitched to the side 51, and side sections 52 by longitudinal lines of stitching 55, Figure 25, forming a pocket 56. The short rib 28 of the long rib 27, Figure 25, is swung upon its hinge so that its inner end extends outwardly beyond the rib 27, and such end is then inserted into the pocket 56, Figure 25, and the side 51 and side sections 52 are then folded transversely upon a line 57. The unit thus produced is now applied to a longitudinally elastic foundation, which might be the front panel 12' of Figure 18, or the sides 11 or any other portion of the girdle or other garment. When thus applied the rib 27 is next to the foundation element and the side sections 52 are next to the same. The folded unit is stitched to the foundation element 12' by longitudinal zigzag lines of stitching 58, terminating at the elevation of the hinge of the short rib and further by lines of zigzag stitching 59. The pocket 56 receiving the inner end of the short rib serves to fixedly attach the end of the rib 27 to the garment, so that it cannot move longitudinally with relation to the same, while the casing or pocket 59' formed by the folded unit and the foundation element 12' is freely slidable upon the rib 27. This will permit of the longitudinal stretching of the foundation element 12', while the rib or ribs 27 would retain it flat against folding or wrinkling. The pocket 56 and associated elements may be employed to attach either the upper or lower end of the rib 27 to the foundation element.

In Figures 29, 30, 31, and 32, I have shown a further modification wherein a longitudinally elastic strip or tape 60 is provided, which is applied to a vertically and longitudinally elastic foundation element or section 61. The tape 60 when applied to the section 61 overlaps the same and extends upwardly beyond it. These overlapping parts are secured together by a zigzag line 62 terminating at points 62'. The strip 60 is now folded downwardly upon a transverse line 63, overlapping the flap 64 and section 61. These overlapping parts 60, 64, and 61, are now secured together by zigzag lines of stitching 65, terminating at 65'; and zigzag lines of stitching 66 connecting elements 60 and 61. The strip 60 forms with the section 61 an elongated pocket 66' and the rib 21 carrying the short rib 28 is now inserted into this pocket 66'. The short rib 28 is between the body and the end of the long rib. A transverse line of stitching 67 is provided, passing through an elongated horizontal slot 68 formed in the upper end of the short rib 28 and secures this short rib to the upper end of the section 61 or garment. When the strip 60 is applied to the section 61 the flap 64 is next to the section 61 and the strip 60 may be applied to the inner or outer face of the section 61.

It is to be understood that the forms of my invention herewith shown and described are to be taken as preferred examples of the same and that various changes in the shape, size, and arrangement of parts may be resorted to, without departing from the spirit of my invention or the scope of the subjoined claims.

Having thus described my invention, what I claim is:

1. A stiffening unit comprising a flexible fabric casing including opposed sides, one side being at least in part elastic, means forming pockets near the ends of the casing, said pockets having their inner ends spaced longitudinally of the casing, said opposed sides having their adjacent edges disconnected throughout the major portion of their length, and a stiffening element within the casing, said stiffening element including a long rib and short ribs hinged to the ends of the long rib, the short ribs extending into the pockets, one side of the casing to be stitched to a garment part.
2. A stiffening unit comprising a flexible casing including opposed sides, one side being folded transversely upon itself near its ends for forming pocket sides, the inner ends of the pocket sides being spaced longitudinally of the side which carries them, the other side being at least in part elastic and secured to the pocket sides, the pocket sides being adapted to form pockets with the first named side, said pockets having their inner ends spaced longitudinally of the casing, the adjacent longitudinal edges of the opposed sides being disconnected throughout the major portion of their length between the pockets, and a stiffening element within the casing including a long rib and short ribs hinged thereto near the ends of the long rib, the short ribs extending into the pockets, said casing to be secured to a garment part.
3. A stiffening unit comprising a two layer first side folded transversely upon itself near its ends for providing pocket sides forming pockets with the first side, said pockets having their inner ends spaced longitudinally of the first side, a second side which is at least in part elastic secured to the pocket sides, the first and second sides having their adjacent edges between the pockets disconnected throughout the major portion of their length, and a stiffening element arranged between the first and second sides and including a long rib and short ribs hinged to the ends of the long rib, the outer ends of the short ribs extending between the pocket sides and first side, the first side to be stitched to a garment part.
4. A stiffening unit comprising a two layer first side folded transversely upon itself near its ends for providing pocket sides which form pockets with the first side, said pockets having their inner ends open and spaced longitudinally of the first side, a second side which is at least in part elastic and including two layer end portions attached to the pocket sides, the adjacent edges of the first and second sides being disconnected throughout the major portion of their length between the pockets, and a stiffening element arranged between the first and second sides and including a long rib and short ribs hinged to the ends of the long rib, the outer ends of the short ribs being covered by the pocket sides and the inner ends of the short ribs being covered by the two layer end portions, the first side being stitched to a garment part.
5. A stiffening unit comprising a first side foldable transversely upon itself near its ends for providing pocket sides forming pockets with such first side, the inner ends of such pockets being open and spaced longitudinally of the first side, a second side which is at least in part elastic secured to the pocket sides, the first and second sides having their adjacent longitudinal edges disconnected between the pockets throughout substantially their entire length, a stiffening element arranged between the first and second sides

and including a long rib and short ribs hinged to the ends of the long rib, the outer ends of the short ribs extending between the pocket sides and first side, and means secured to one side between the pockets to prevent the removal of the stiffening element from between said sides.

6. A stiffening unit comprising a first side including a fabric blank folded longitudinally upon itself to provide a layer and layer sections arranged in overlapping relation, the longitudinally folded blank being folded transversely near its ends to provide pocket sides forming with the first side pockets, said pockets having their inner ends open and spaced longitudinally of the first side, a second side including a longitudinally elastic fabric folded transversely upon itself near its ends for providing flaps arranged in overlapping relation to the second side, means securing the ends of the second side to the pocket sides, the first and second sides having their longitudinal edges between the pockets disconnected throughout the major portion of their length, and a stiffening element arranged between the first side and second side and including a long rib and short ribs hinged to the ends of the long rib, the outer ends of the short ribs being covered by the pocket sides and the inner ends of the short ribs being covered by the flaps.
7. A stiffening unit comprising a first side including an elongated fabric blank folded longitudinally upon itself to provide a layer and layer sections arranged in overlapping relation, the longitudinally folded blank being transversely folded near its ends for forming pocket sides, each pocket side including a layer and opposed layer sections, the pocket sides forming with the first side end pockets having their inner ends open and spaced longitudinally of the first side, a second side including an elongated longitudinally elastic blank folded transversely upon itself near its ends for providing flaps, the folded ends of the second side being inserted between the layers and layer sections of the pocket sides and stitched to the pocket sides, the first and second sides having their adjacent edges between the pockets disconnected throughout the major portion of their length, and a stiffening element arranged between the first side and second side and including a long rib and short ribs hinged to the ends of the long rib, the outer ends of the short ribs being covered by the pocket sides and the inner ends of the short ribs being covered by the flaps.
8. A stiffening unit comprising a first side including a fabric blank folded transversely upon itself near its ends to provide pocket sides arranged in overlapping relation to the first side and forming with the first side end pockets, said end pockets having their inner ends open and spaced longitudinally of the first side, a second side which is at least in part elastic arranged opposite to the first side and narrower than the first side, means securing the ends of the second side to the pocket sides, and a stiffening element arranged between the first side and second side and including a long rib and short ribs hinged to the ends of the long rib, the outer ends of the short ribs being covered by the pocket sides, the arrangement being such that longitudinal lines of stitching following the longitudinal edges of the first side and pocket sides may secure the first side and pocket sides to a garment part without engaging the second side.
9. A stiffening unit comprising a first side including a fabric blank folded upon itself near its ends for forming pocket sides, a second side in-

cluding a longitudinally elastic section, non-elastic attaching elements, each attaching element including a fabric blank folded longitudinally upon itself to provide overlapping layer and layer sections, the ends of the elastic section being inserted between the layers and layer sections of the attaching elements and secured thereto, the opposite ends of the attaching elements being secured to the pocket sides, and a stiffening element arranged between the first side and second side and including a long rib and short ribs hinged to the ends of the long rib.

10. A garment, a stiffening unit for coaction with the garment, the stiffening unit comprising a first side having its ends folded inwardly upon itself for forming pocket sides which form end pockets with the first side, said end pockets having their inner ends open and spaced longitudinally of the first side, a second side which is at least in part elastic disposed opposite to the first side and narrower than the first side, means securing the ends of the second side to the pocket sides, a stiffening element arranged between the first side and second side and including a long rib and short ribs hinged to the long rib near its ends, the outer ends of the short ribs being covered by the pocket sides, and longitudinal lines of stitching passing through the first side, pocket sides and garment and not through the second side.

11. A casing for a stiffening element including a long rib and short ribs hinged to the ends of the long rib, said casing including a non-elastic fabric blank folded upon longitudinal edges to provide a layer and layer sections arranged in overlapping relation, the folded blank forming a first side which is folded transversely near its ends for providing pocket sides which form end pockets with the first side, said end pockets having their inner ends open and spaced, and a second side which is at least in part elastic secured to the pocket sides and disposed opposite to the first side, the first and second sides having their adjacent longitudinal edges between the end

pockets disconnected throughout the major portion of their length.

12. A stiffening unit comprising a first side having means secured to one end thereof for forming an end pocket having its inner end open, a second side which is at least in part elastic secured to the pocket forming means, means connecting the opposite ends of the first side and second side, the inner open end of the pocket being spaced from the connecting means, the first and second sides having their adjacent longitudinal edges between the pocket and connecting means disconnected throughout the major portion of their length, and a stiffening element arranged between the first side and second side and including a long rib and a short rib hinged to one end of the long rib, the short rib projecting into the pocketing forming means.

13. A stiffening unit to be applied to the body of a garment and formed separate therefrom, comprising an elongated separate fabric strip folded at its end transversely to form a flap which is stitched to the strip for providing a pocket, said pocket having its inner end open and spaced from the opposite end a stiffening rib, and a short rib hinged to the end of the stiffening rib and extending into the pocket and means to secure the separate strip to the body.
